D19-44. OR D11,795 EX

No. 11,795

June 1, 1880

UNITED STATES PATENT OFFICE

LE ROY W. FAIRCHILD, OF NEW YORK, N. Y.

DESIGN FOR PENCIL-CASES.

SPECIFICATION forming part of Design No. 11,795, dated June 1, 1880.

Application filed March 24, 1880. Term of patent 7 years.

To all whom it may concern:

Be it known that I, LE ROY W. FAIRCHILD, of the city, county, and State of New York, have produced a new and original Design for 5 Pencil-Cases or other small implement cases intended to be worn suspended from a chain or cord, of which the following is a full, clear, and exact description, reference being had to the accompanying photographic illustration 10 or drawing, making a part of this specification.

A represents the barrel or tube, in which the pencil or other implement is concealed, slightly enlarged at the upper end, from which 15 the wire loop B springs. B is a wire loop in an elliptic form, springing out of the upper end of the barrel or tube A, and having its axis in the same line or plane with that of said barrel or tube. C is an eye attached to

the tube or barrel A near its upper end. D 20 is a ring suspended from the eye C.

The pencil-case may be made of materials having the same or different colors, and the surface may be left plain or variously ornamented by engraving, or engine-turning, or 25 by other means; but I do not consider color or ornamentation an element in my design.

What I claim as my invention is—

A design for a pencil-case or other small implement case having the tube or barrel A, 30 the elliptic wire loop B, the axis of which is in the same plane with the barrel, the eye C, and the ring D, substantially as shown and described.

LE ROY W. FAIRCHILD.
